UNITED STATES PATENT OFFICE.

JOHN A. CUNNINGHAM, OF BETHLEHEM, PENNSYLVANIA.

AUTOMOBILE SIGNAL.

Application filed April 10, 1924. Serial No. 705,555.

To all whom it may concern:

Be it known that I, JOHN A. CUNNINGHAM, a citizen of the United States, residing at Bethlehem, in the county of Northampton and State of Pennsylvania, have invented certain new and useful Improvements in Automobile Signals; and I do declare the following to be a full, clear, and exact description of the invention, such as will enable others skilled in the art to which it appertains to make and use the same.

My invention relates to improvements in signals for use on automobiles to show the intentions of their drivers, with respect to direction of travel, and the object is to provide a simple and inexpensive device of this character which will be highly efficient and in every way desirable.

With the foregoing in view, the invention resides in the novel subject matter herein-after described and claimed, the description being supplemented by the accompanying drawings.

Figure 1 is a perspective view showing the invention applied to an automobile.

Figure 2 is a perspective view showing the casing body and its removable end member in juxtaposition, the rear side of the casing body being shown.

Figure 3 is a front elevation.

Figure 4 is an inner end view.

Figure 5 is a top plan view.

Figure 6 is a central vertical longitudinal sectional view.

Figures 7 and 8 are respectively vertical and horizontal sections on lines 7-7 and 8-8 of Fig. 6.

Figure 9 is a perspective view of one of the reflectors and partitions which divide the casing into different signaling compartments.

In the drawings above briefly described, the numeral 1 designates a vertically disposed inner end member for a signaling casing 2, said end member 1 having a continuous side flange 3 which projects outwardly and receives the open inner end 4 of the casing. The end member 1 is provided with suitable brackets 5 by means of which it may be secured to a windshield frame or other desired part of an automobile, and it may here be stated that while I have shown the signal constructed for use on the right-hand side of a machine, it may also be manufactured to be applied to the left side.

In the present showing, four sockets 6, 7, 8 and 9 pass through the flange 3 at one side of the casing and carry illuminating bulbs 10, 11, 12 and 13. The passage of current through the wires 14 which lead to the several sockets is controlled by a suitable switch which may be of any desired character and located at any convenient point. I have indicated a multiple switch 15 mounted on the steering wheel of the machine, for this purpose.

In the present showing, I provide pivoted hasps 16 carried by the casing end 1, to swing over staples 17 carried by the casing 2, suitable anti-rattling keys 18 being preferably passed through said staples, as shown. When these keys are removed and the hasps 16 released, the entire casing 2 may be detached from the end member 1, giving access to all of the bulbs 10, 11, 12 and 13, as well as making all internal parts of the casing 2 accessible, for instance for cleaning or repairing.

In a plane between the bulbs 12 and 13, the casing 2 is horizontally partitioned by a reflecting plate 19 whose edges are slidably received in opposed internal grooves 20 formed in the front and rear walls of said casing. Above the reflector 19, the casing is further divided by lower and upper reflecting plates 21 and 22, having their edges received in grooves 23 and 24. All of the grooves are preferably formed by outwardly stamping the casing sides, as shown.

By the reflecting plates 19, 21 and 22, the interior of the casing is divided into a lower signaling compartment 25 illuminated by the bulb 13, an upper compartment 26 illuminated by the bulb 10, and two intermediate compartments 27 and 28 in which the bulbs 11 and 12 respectively, are located. The rear sides of the compartments 25 and 28 are preferably provided with a traffic mirror 29 in a suitable frame 30, while the front sides of these compartments are equipped with signaling panels 31 and 32 of glass or celluloid. The panel 32 is preferably white or clear and the bulb 12 may well burn continuously. This panel is horizontally elongated as seen in Fig. 3 and thus, a very distinctive light is constantly displayed to attract attention to the signal, the shape of the panel serving to effectively distinguish it from ordinary running and signal lights. The panel 31 may be suitably shaped, but is preferably elongated as shown

in Fig. 3. Either this panel is colored or the bulb 13 co-operating therewith is colored, so that a distinct colored light may be displayed at the front side of the signal 5 casing, whenever the driver intends to pass a machine going in the same direction. Thus, the driver of another machine coming 10 in the opposite direction is notified of the first driver's intentions and he is consequently more apt to allow him plenty of room. I prefer that the panel 31 shall disclose a blue light, but some other color could be used if desired.

The front and rear sides of the compartments 26 and 27 are provided with signaling 15 panels 33 and 34 to indicate right and left-hand turns, when illuminated by the bulbs 10 and 11. The reflector or partition 22 between these compartments 26 and 27 and 20 the partition member 21 between the compartments 27 and 28, are each preferably of somewhat arched formation as shown, with the height of the arch preferably increasing gradually away from the end member 1, to 25 give better reflecting qualities. The upper sides of each of these members 21 and 22, are provided with central vertical longitudinal flanges 35 which are of less height than the compartments into which they extend. These flanges are in line with the 30 centers of the bulbs 10 and 11 and they are formed with reflecting surfaces so that they will reflect light from said bulbs, both forwardly and rearwardly through the panels 33 and 34. Preferably, in the formation of 35 either the member 21 or 22, a single piece of sheet metal is bent upon itself at its center as indicated at 36 in Fig. 9 only. The portions of the metal adjacent the bend 40 form the flange 35 and on lines 37 spaced from said bend, the two halves of the piece of metal are bent horizontally outward to form the reflecting and partition member 21 or 22, as the case may be. These two 45 members 21 and 22 extend entirely from end to end of the casing and the opposite ends of the latter are preferably grooved at 38 to receive them, and at one end, the flanges 35 are formed with notches 39 to receive the 50 bulbs 10 and 11.

To provide additional reflecting means for the compartment 28, the rear edge of the plate 19 is preferably formed with an up-standing reflecting flange 40 whose upper 55 edge is preferably bent outwardly at 41 into the next adjacent groove 23. A reflecting plate 42 is also by preference provided in the bottom of the compartment 25, the rear edge of this plate 42 having an up-standing reflecting flange 43 whose upper 60 edge 44 is by preference bent outwardly into one of the grooves 20. To receive the ends of the partition 19, the ends of the casing may have grooves 38^a, similar to the 65 grooves 38 above described.

In using the device, the white panel 32 is continuously illuminated at night and turns intended, to the right or left, are indicated by means of the panels 33 and 34, by illuminating either the bulb 10 or the bulb 11. 70 The provision of the reflectors 21 and 22 with their flanges 35, insures that the light from these bulbs shall effectively illuminate the panels at both the front and rear sides of the device. When the driver of the machine intends to pass another machine going 75 in the same direction, the panel 31 is illuminated, preferably with a blue light as above set forth, and thus anyone coming in the opposite direction is given warning of 80 the driver's intentions, so that he may be given plenty of room to pass. The reflecting plates 19 and 42 and their flanges 40 and 43 insure ample illumination of the panels 31 and 32.

In the preferred form of construction, a continuous rib 45 is stamped out around the inner end of the casing 2 to abut the flange 3, and the portion of said casing, receivable within said flange 3, has been shown as 90 formed with slots 46 leading to the several grooves above described, said slots preferably having enlarged front ends 47 so that the members 19, 21 and 22 may be readily slid into place whenever they have been removed, for instance, when cleaning is necessary. The inner end of the casing 2 in addition to having the slots 46, is provided with notches 48 which receive the sockets 6, 7, 8 and 9.

It will be seen from the foregoing that a rather simple, yet a very efficient and desirable signaling device has been provided, and while excellent results may be obtained from the exact details disclosed, I wish it understood that within the scope of the invention as claimed, numerous modifications may be made.

I claim:

1. In a device of the class described, the combination of a signal casing, bulb sockets mounted in one end of said casing, said casing having internal guideways extending longitudinally along opposite sides, a partition plate slidably received in said guideways and dividing said casing into compartments, the side edges of said plate fitting in said guideways, said plate being transversely arched and resilient to adapt it to fit tightly against and in said guideways, and a reflecting flange projecting laterally from the convex side of said plate into one of said compartments and extending longitudinally of said plate intermediate of its side edges, said flange being of less height than the last mentioned compartment to permit said plate to flex to fit said guideways.

2. In a device of the class described, the combination of a signal casing, bulb sockets mounted in one end of said casing, said cas-

ing having internal guideways extending longitudinally along opposite sides, a partition plate slidably received in said guideways and dividing said casing into compartments, the side edges of said plate fitting into said guideways, said plate being transversely arched and resilient to adapt it to fit tightly against and in said guideways, and flanges extending laterally from inner edges of the two halves of said plate away from the convex sides thereof, said flanges being disposed back to back and being integrally connected along their outer edges, and forming a two-faced reflector of less height than the compartment in which it is disposed to permit said plate to flex to fit said guideways.

3. In an automobile signal, a casing hav-

ing a removable end member and bulb sockets carried thereby in vertically spaced relation, the front and rear sides of said casing having opposed inwardly facing horizontal grooves, and vertically spaced partitions having their edges slidably received in said grooves to divide the casing into separate signaling compartments, one of said partitions having a vertically extended longitudinal reflector at one edge extending to the next partition, said reflector having its free edge bent outwardly to form an anchoring flange received in one of the receiving grooves of said next partition.

In testimony whereof I have hereunto affixed my signature.

JOHN A. CUNNINGHAM.
